UNITED STATES PATENT OFFICE.

HENRY P. FOUQUÉ, OF NEW YORK, N. Y.

DESIGN FOR A RUBBER PAD FOR BOOTS AND SHOES.

48,932.

Specification for Design.

Patented Apr. 25, 1916.

Application filed January 15, 1916. Serial No. 72,363. Term of patent 14 years.

To all whom it may concern:

Be it known that I, HENRY P. FOUQUÉ, a citizen of the United States, residing at the city of New York, borough of Brooklyn, county of Kings, State of New York, have invented a new, original, and ornamental Design for a Rubber Pad for Boots and Shoes, of which the following is a specification, reference being had to the accompanying drawing, forming part thereof.

Figure 1 is a side elevation of a rubber

pad for boots and shoes embodying my new design; and Fig. 2 is an inverted plan view thereof.

I claim:

The ornamental design for a rubber pad for boots and shoes, as shown.

HENRY P. FOUQUÉ.
